UNITED STATES PATENT OFFICE.

CHARLES L. AMES, OF OAK PARK, ILLINOIS.

DESIGN FOR A RIM FOR BICYCLE-WHEELS.

SPECIFICATION forming part of Design No. 23,015, dated January 23, 1894.

Application filed December 22, 1893. Serial No. 494,471. Term of patent 14 years.

To all whom it may concern:

Be it known that I, CHARLES L. AMES, a citizen of the United States, residing at Oak Park, in the county of Cook and State of Illinois, have invented and produced a new and original Design for Rims of Bicycle and other wheels, of which the following is a specification, reference being had to the accompanying drawings, forming a part thereof.

My invention has relation to designs for rims of bicycle and other wheels, and consists in the new and original shape or configuration of the rim as hereinafter particularly described in the specification and illustrated in the drawings.

In the accompanying drawings, Figure 1 represents a side elevation of my new and original form of a rim, and Fig. 2 represents a cross section of the same.

A is the rim. At the middle of the rim there is a part, A', which is straight in cross section and perpendicular to the plane of the wheel. From each side of the part, A', a part, A², extends outward away from the middle of the wheel, whereby the channel, a', having a flat bottom in cross section is formed. From each part, A², a part, A³, extends away

from the middle of the rim and perpendicular to the plane of the wheel, thus forming at each side of the channel, a', a ledge or table, 30 a³. The width of each of the parts, A³, is approximately one half of the width of the channel, a'. From the outer margin of each part A³ a part, A⁴, extends outward away from the center of the wheel and the middle of the 35 rim. These parts A⁴ are in a general way perpendicular to the portion of the rim composed of the parts, A³, A², and A'. The parts, A², are of equal width. The parts, A³, are of equal width. The parts, A⁴, are of equal 40 width.

Having thus described my invention, what I claim, and desire to secure by Letters Patent, is—

The design for a rim for bicycle and other 45 wheels substantially as described and illustrated in the accompanying drawings.

In testimony whereof I affix my signature, in presence of two witnesses, this 9th day of December, 1893.

CHARLES L. AMES.
